UNITED STATES PATENT OFFICE.

JOSEPH K. DAVIS, OF WATERBURY, CONNECTICUT, ASSIGNOR TO SCOVILL MANUFACTURING COMPANY, OF WATERBURY, CONNECTICUT, A CORPORATION OF CONNECTICUT.

AIR-DISTRIBUTER FOR LAMP-BURNERS.

1,337,825.

Specification of Letters Patent. Patented Apr. 20, 1920.

Application filed January 28, 1919. Serial No. 273,571.

To all whom it may concern:

Be it known that I, JOSEPH K. DAVIS, a citizen of the United States, residing at Waterbury, in the county of New Haven 5 and State of Connecticut, have invented a certain new and useful Improvement in Air-Distributors for Lamp-Burners, of which the following is a full, clear, and exact description.

10 The flame of lamps burning coal-oil or kerosene and using the ordinary burners, is often flickering and unsteady, due in large measure if not wholly to strong induced air-currents, and many devices, known as "air-distributors," have been introduced for correcting this. Some of these devices have been applied to the wick-tube of the burner, and others to the dome or cone or other part 15 of the burner. All such devices require 20 cleaning at times, and accessibility to them is not always free, especially when they are fixtures.

The object of the present invention is to provide a very simple device, adapted to 25 break up the air-currents and thus free the flame from flickering and unsteadiness, and also adapted to be readily placed upon and removed from the wick-tube at pleasure.

30 The invention consists of a so-called air-distributer, of skeleton form, preferably blanked out of sheet metal, although it may be made of wire, bent to clasp the wick-tube with sufficient firmness to retain its place thereon, and having flared portions arranged alongside the wick-tube, but spaced apart therefrom and standing at about the level of the top of the wick-tube or base 35 of the flame so as to intercept the air-currents and cut or break them up, the device 40 being readily applied to and removed from the wick-tube by any one, as I will proceed now to explain and finally claim.

In the accompanying drawing illustrating 45 the invention, in the several figures of which like parts are similarly designated, Figure 1 is a side elevation of a lamp burner with the cone or dome in section, showing the sheet metal form of the device in position. Fig. 2 is a similar view taken at right angles 50 to Fig. 1. Fig. 3 is a top plan view, partly in section, with the cone or dome removed. Fig. 4 is a plan view of the blank of the

sheet-metal construction before folding or bending. Fig. 5 is a perspective view of the sheet metal device detached. Fig. 6 is a 55 perspective view of a wire construction, and Fig. 7 is an edge view thereof.

The burner 1 herein shown is of a well known type and needs no further description to render the present invention intelligible, except to say, that it has a flat wick-tube 2 extending into and inclosed by the dome or cone 3, which is hinged at 4 so as to be movable to cover and uncover the wick-tube. 60

The device of this invention herein designated 5, as shown in Figs. 1 to 5, is blanked out of sheet metal, preferably steel, in the form shown in Fig. 4, and then it is folded upon itself along a transverse median line 70 so as to form substantially parallel spaced-apart portions 6 which extend to a point about where the side members are nearest or converge, and then the free ends 7 are flared and their transverse terminals 8 returned, that is to say, bent inwardly, as seen in Figs. 2, 3 and 5. In side view, Fig. 1, and in top plan view, Fig. 3, the outline is substantially of X form, while in edge view, Fig. 2, the outline is substantially of Y 80 form. The parallel portion forms a socket which is sufficiently elastic to grip the wick-tube and hold the device steadily in place, and yet allow it to be easily placed and removed by any one. The flared sides and 85 their transverse terminals cross the path of the air-currents and break them up or cut them and thus prevent flickering or unsteadiness of the flame.

The device when made of steel may be 90 brass-plated or otherwise finished.

The modification shown in Figs. 6 and 7 embodies substantially the same structural characteristics as just described, excepting that wire is substituted for sheet metal, and 95 the upper ends are not returned. Copper wire is excellent for this construction, especially as it will not collect soot, but it has a tendency in use to become soft and is readily deformed in removing it from and replacing it upon the wick-tube. The steel or blanked form will collect soot more or less readily, but it is capable of being readily cleaned, and in addition it is hard and re- 100

tains its shape and may be economically manufactured.

Other variations are deemed as within the principle of the invention as hereinafter 5 claimed.

The peculiar shape of these devices is the result of experiments. The efficiency of the wick-tube gripping portion would seem to be obvious; but it is to be said that the upper 10 spreading portion of the device serves to break up the air-currents in such way that flickering or unsteadiness of the flame is practically stopped. The lower portion being in contact with the wick-tube and the 15 upper portion being near the flame, the whole device becomes thoroughly heated and acts upon the burning fluid to generate gas or vapor, thus producing rather more light than a burner without the device. Because 20 the device does increase the candle power of the burner it may be approximately referred to as a "booster."

The device can be sold entirely separate 25 from the burner, and can be applied without difficulty by any user. Further, it is readily removed for cleaning it and the burner and for trimming the wick, and as easily restored, or replaced; and in these respects it is superior to those devices that are fixed 30 to some portion of the burner, such as its cone or dome.

The device may be made not only of sheet metal or round wire, as shown, but flat steel

wire or wire of other cross-section may be employed in the manufacture of the device. 35

What I claim is:—

1. An air-distributer for lamp burners, comprising a metal skeleton having its lower portion made substantially parallel and forming a socket to grip the wick-tube of 40 the burner, and its upper portion flared to cut the air-current at about the base of the flame.

2. An air-distributer for lamp burners, comprising a sheet metal skeleton having a 45 parallel sided lower socket portion, to grip the wick-tube, and a flared upper portion adapted to stand in the zone of the base of the flame.

3. An air-distributer for lamp burners, 50 folded to form a parallel sided lower portion, the sides of which converge centrally, and flared thence upwardly.

4. An air-distributer for lamp burners, 55 comprising a sheet metal skeleton folded upon itself and having converging sides in substantially parallel relation to grip the wick-tube of the burner, and thence flaring outwardly and having their transverse terminals returned.

In testimony whereof I have hereunto set my hand this 27th day of Jan. A. D. 1919.

JOSEPH K. DAVIS.
